Primary Examiner—A. Hugo Word*Assistant Examiner*—Holly Bayham*Attorney, Agent, or Firm*—Fitzpatrick, Cella, Harper & Scinto[57] **CLAIM**

The ornamental design for a protective cover for a concrete reinforcing bar, as shown and described.

DESCRIPTION

FIG. 1 is a perspective view of a protective cover for a concrete reinforcing bar showing our new design; FIG. 2 is an enlarged top view thereof; FIG. 3 is an enlarged side view with the remaining sides being mirror images; and, FIG. 4 is an enlarged bottom view thereof. The broken line showing of a fragmented reinforced bar is for illustrative purposes only and forms no part of the claimed design.
